TOY TRACTOR TYPE AIRPLANE CARRIER

Allan J. Alvane, Arlington Heights, Ill., assignor to Sears, Roebuck and Co., Chicago, Ill., a corporation of New York

Filed Dec. 1, 1960, Ser. No. 63,054

Term of patent 3½ years

(Cl. D34—15)

FIG. 1 is a front perspective view of a toy tractor type airplane carrier embodying my new design, and,

FIG. 2 is a rear perspective view of the same.

The dominant feature of my design resides in the portion shown in full lines.

I claim:

The ornamental design for a toy tractor type airplane carrier, substantially as shown and described.
